BOAT WHEELBARROW

Albin A. Bjork, Ashland, Wis.

Original application August 12, 1943, Serial No. 498,354, now Patent No. 2,361,592, dated October 31, 1944. Divided and this application April 26, 1944, Serial No. 532,838

1 Claim. (Cl. 9—1)

This application is a division of my application filed August 12, 1943, Serial No. 498,354, now Patent No. 2,361,592, dated October 31, 1944.

The invention has for an object to enable the ready handling and portage of small boats, such as canoes and the like, by enabling the quick conversion of the boat into a barrow-like device having a wheel at one part upon which the boat may be rested, and handles at the opposite part which may be grasped to push the boat about upon the wheel.

It is a special aim of the invention to arrange this device in such manner that it may be readily used in placing a boat in inverted position upon the roof of an automobile, as well as enabling its ready portage by rolling it upon the ground from place to place.

A special aim of the invention is to provide a novel means of mounting a barrow wheel upon canoes and boats in a folding arrangement whereby the boat wheel will not interfere with use of the boat for ordinary purposes, such as fishing, or paddling in the ordinary way, and so that the wheel will not be a conspicuous or objectionable projection upon the boat when the latter is in use upon the water. Another important aim of the invention is to provide a novel combination of paddle, boat and barrow wheel in such manner that the three coact to provide a unitary structure which may be rolled about upon the wheel.

Additional objects, advantages and features of invention reside in the construction, arrangement and combination of parts involved in the embodiment of the invention, as will be more readily understood from the following description and accompanying drawing, wherein:

Figure 1 is a view showing the combined boat and barrow ready for portage, but inverted upon the roof of a passenger automobile shown in dotted lines.

Figure 2 is a similar view showing the manner of emplacement or removal of the boat upon such vehicle.

Figure 3 is a view showing a further stage in the removal, or an earlier stage in its emplacement.

Figure 4 shows the manner of moving or porting the boat by rolling it upon the barrow wheel.

Figure 5 shows the manner of connecting the paddles to the body of the boat for use as barrow handles.

Figure 6 is a side elevation partly in section of the bow of a boat upon which my invention is embodied.

Figure 7 is a detail of the mounting bracket involved in the construction of Figure 6.

There is illustrated a boat hull 10 of conventional form, in the present instance having a flat stern 11, although my invention is also applicable to canoes having both ends of the same shape as the bow 12 shown in the present boat. The bow of the boat in the present instance is constructed with a small deck 13, which due to 10 the converging of the gunwales 14 is triangular in shape.

In Figure 6 there is shown the mounting of the wheel, in which a bracket plate 15 has mounted thereon two triangular plates 16 arranged in 15 parallel relation, each having a bearing 17 in which an axle 18 is secured arranged to carry a wheel 19 trunnioned therein, in the conventional way. At its rear edge, as viewed in full lines in Figure 6 and 7, the plate 15 is formed 20 with hinge knuckles 20 at each side, and a hinge butt member 21 has a knuckle portion 22 set between the ears 23 and a common pintle engaged therethrough, as shown. The butt plate 21 is suitably apertured to receive screw fastenings or the like, and as shown in Figure 6 is secured to the rear edge portion of the deck 13 in the bow 12 of the boat, in such manner that the plate 15 may be swung into position to rest flat upon the deck 13 to which it may be secured in any conventional way, if desired, by releasable fasteners 24. By raising the forward portion 25 of the bracket plate 15 from the position shown in full lines in Figure 6, this plate together with the wheel may be swung rearwardly and downwardly, to the position dotted in Figure 6, wherein the wheel lies below the deck and plate 15 extends pendently, as dotted.

Paddles 25 are provided, which may be of 40 conventional form, and on each side of the boat at the stern, oar locks 26 are mounted, while forwardly of the stern a distance and secured upon the inner sides of the brackets 27 are mounted, one only being shown, these brackets 45 being retained permanently upon the sides of the boat, and being arranged for releasable engagement with the blade of the paddle when desired. The bracket, in the present instance, at 27, is substantially in the form of an inverted U, the arms being of sufficient length to receive a substantial part of the blade 28 of the paddle, one arm being secured against the side of the boat as shown, in any approved manner, while the other is provided with a thumb-screw 29, or 50 55 the like, which may be screwed inwardly against

the blade of the paddle when set within the bracket arms, as shown in Figure 5.

For portage purposes, two paddles 25 are provided, and in order to move the boat, the blades of the paddles are engaged in the brackets 27 and secured by means of the clamp screw 29 while the handle portions of the paddles are laid in the oar-locks 26, as shown in Figure 5.

The paddles having been secured in position as shown in Figure 5, the boat may then be inverted until its bow is supported in the wheel 19, as shown in Figure 4, and the rearwardly projecting ends of the handles of the paddles are grasped by the porter, as also shown in Figure 4. The device may be thus pushed forwardly upon the wheel 19 and guided in the same manner as a wheel-barrow.

In order to place the boat upon a vehicle, it may be inverted after the proper positioning of the wheel and handles of the paddles, and in the case of a car with long sloping back, the bow end may be swung into position so that the wheel may rest upon the sloping back of the vehicle, as shown in Figure 3, after which it may be pushed forwardly until the gunwales rest upon the roof of the car. In order to avoid marring the finish of the automobile, a common form of luggage brackets may be provided upon the top of the car to support the boat, and in Figures 1 and 2, there are illustrated members of such luggage carrier, consisting in two transverse bars 30, having suction cups 31 on their lower sides which may be removably secured upon the surfaces of the car in the desired positions in the manner familiar in the use of such suction cups.

In such case, after the positioning of the boat as shown in Figure 3, it may be rolled forwardly until the wheel passes over both bars 30, sub-

stantially to the position shown in Figure 2, after which the rear portion of the boat may be lowered until the gunwales rest upon the bars 30, as shown in Figure 1. If preferred, the bow end portion of the boat may be raised and swung into position with the wheel resting upon the hood portion of the vehicle, then the stern portions swung around and over the body of the vehicle while the boat is inverted to the position shown in Figure 1. In order to remove the boat, the operations for its emplacement may be reversed, as will be understood. Other procedure for emplacement and removal of the boat from a vehicle may suggest themselves to those accustomed to handling boats and canoes, as will be appreciated.

While I have disclosed my invention in detail in the best form known to me, it will, nevertheless, be understood that this is purely exemplary, and that various modifications in the construction, arrangement and combination of parts may be made therein without departing from the spirit of the invention except as more specifically limited in the appended claim, wherein I claim:

25 In combination, a boat hull having a forward deck, a wheel mount complementary to the deck for support of said hull at times, said wheel mount being positioned in the medial longitudinal axis of the hull and deck, and comprising a hinge leaf connected to an edge of the deck, a plate hingedly connected to said hinge leaf, securing means between said deck and said plate, said securing means being releasable to permit said plate to be swung to a position clear of the deck, said plate having a pair of spaced parallel bearing plates, and a wheel revolutely mounted between said bearing plates.

ALBIN A. BJORK.
